UNITED STATES PATENT OFFICE.

JOHN S. O'CONNOR, OF WHITE MILLS, PENNSYLVANIA.

DESIGN FOR THE ORNAMENTATION OF GLASSWARE.

SPECIFICATION forming part of Design No. 18,732, dated November 13, 1888.

Application filed October 9, 1888. Serial No. 287,702. Term of patent 7 years.

To all whom it may concern:

Be it known that I, JOHN S. O'CONNOR, a citizen of the United States, residing at White Mills, in the county of Wayne and State of Pennsylvania, have invented a new and original Design for the Ornamentation of Glassware; and I do hereby declare the following to be a full, clear, and exact description of the same, such as will enable others skilled in the art to which it appertains to make and use the same.

My new design is for the surface ornamentation of glass articles, such as plates, bowls, and dishes; and it is illustrated in drawings accompanying this specification, in which—

Figure 1 is a plan view of such an article, and Fig. 2 a vertical section. The center of the design is formed by two intersecting squares bounding an octagonal frusto-pyramidal figure, *b*, on which is formed a multipointed star, *c*. The squares are formed by triple parallel lines *a a' a''*. At each point of the squares the lines *a a'* are produced out to the edge of the bowl or other article on such a curve as to cause them to converge to an intersection, *c'*, at that point, forming a double-pointed loop from each corner of each square to the edge. Alternating with these loops and intersecting them are pointed figures, formed by producing out the lines *a a''* to the edge, where they intersect, as at *c''*, the

line *a'* being forked, as at *a''*. This results in the formation of fan-shaped figures between the points *c'* and *c''*, which are ornamented by surface-lines and peripheral scallops, as 35 shown. The frusto-pyramidal figures bounded by the extended lines *a a' a''* are ornamented on the surface by close cross-hatching, as at *e*, or by wide-open cross-hatching, as at *f*, or by surface-lines and multipointed stars, as at *g h*. 40 The intersection of these lines in the squares also forms small pyramidal figures, as *i*, between them.

What I claim is—

The design herein shown and described for 45 the surface ornamentation of glassware, the same consisting of two central intersecting squares, loops formed by producing the lines at the corner of each square out to the edge, alternating Gothic pointed figures formed by 50 producing the lines of adjacent corners of different squares out to the edge, fan-shaped figures between the loops and Gothic figures at the edge, and ornamented pyramidal figures bounded by the lines of the squares, looped, 55 and Gothic figures, all substantially as set forth.

In testimony whereof I have affixed my signature in presence of two witnesses.

JOHN S. O'CONNOR.

Witnesses:
